UNITED STATES PATENT OFFICE.

IRVING FLORMAN, OF NEW YORK, N. Y.

LUMINOUS ATTACHMENT FOR INDICATING DEVICES.

1,334,604.

Specification of Letters Patent. Patented Mar. 23, 1920.

Application filed January 2, 1919. Serial No. 269,259.

To all whom it may concern:

Be it known that I, IRVING FLORMAN, a citizen of the United States of America, and residing in the borough of Manhattan, city 5 and State of New York, have invented certain new and useful Improvements in Luminous Attachments for Indicating Devices, of which the following is a specification.

The invention relates to indicating devices 10 for example such as clocks, watches, and gages, to the dials and hands or pointers whereof it is desirous to apply luminous indicating medium so that the indicating device may be read in darkness.

15 In the accompanying drawing Figure 1 represents a plan view of a ring to be secured to the face of a clock or other indicating device. On the ring are formed luminous fields.

20 Fig. 2 represents a plan view of a luminous clip in flat position to be secured, when folded, to the hands of a clock. Fig. 3 is a side edge view of the clip of Fig. 2. Fig. 4 represents the clip of Fig. 2, folded 25 on lines 9—9 of Fig. 2. Fig. 5 represents a clock face with the ring and clip secured respectively to the clock dial and hands.

In carrying out this invention a ring 1 is formed out of paper, or other material, 30 with points or extensions 2 thereon extending inwardly from the body of the ring toward the center of the dial. To the points or extensions 2 a luminous material 3 is applied. The ring 1 has applied to the reverse 35 side thereof glue or other material with which it may be affixed around the periphery of the face of a clock dial 4 or other indicating device. The face 4 of the clock dial or other indicating device, is exposed

40 through the center opening of the ring. The fields or extension 2 as illuminated are spaced around the ring at points corresponding to the markings on the face of the clock dial or other device, which are to be indicated by the luminous material. In the drawing Fig. 5 represents a clock face with the luminous points or extensions lying over the five minute divisions 5, on the dial. The minute graduations 6 are as 45 shown, not covered by the ring 1. The ring is primarily intended to be applied to clocks or other devices which have gone into the hands of users, although the device may also be used as a convenient method of applying 50 luminous material to clocks or the like while still in the manufacturer's hands. A luminous clip 7 is provided for the hands 12

of the indicating device. This clip is stamped out of thin springy metal and has therein an aperture 8, said aperture having angles 60 8^a. The clip is bent at 9—9 across the aperture as shown in Fig. 4 and the edges 10 thereof are brought tightly together by pressure thereon and on the bend 9^a, thus giving the two wings 11 of the clip a tendency to 65 cling together. One of the wings 11 of the clip 7 is given a fanciful formation such as the star 13 shown in the drawings. To this part 13 of the clip a luminous material 14 is applied. The point of the indicating 70 pointer or hands 12 are passed through the aperture 8. The head 12^a of the pointer or hand binds or wedges into the corners of the aperture 8 and the wings 11 come into grasping contact with the stem of the hand or 75 pointers.

The luminous ring 1 may be made in segments for convenience of packing and transportation. If desired, the minute graduations may be covered by the ring and new 80 minute graduations printed on the ring. The ordinary hour figures on the clock dial are thus exposed for ordinary light readings. To read the device in darkness the luminous fields 2 in connection with the smaller 85 hands of the clock show the hour reading and the luminous fields in connection with the larger hand shows the minute readings.

I claim:

1. In combination in a clock, or like device, of a luminous clip having a perforation therein, a pointer through the perforation and a luminous device on the outer surface of the clip, a dial, a thin flexible ring at the periphery of said dial and luminous fields 95 on said ring.

2. In combination, in a clock, a dial on the clock, luminous fields on the dial, a clip having an angular perforation therein, a pointer through said perforation, the pointer 100 being wedged in the angular opening, a thin flexible ring at the periphery of said dial and luminous fields on said ring.

3. In combination in a clock, or the like, a clip having a luminous field thereon, said 105 clip comprising flexible wing sections, an aperture in the clip, a pointer through the aperture and the wing sections in holding contact with the pointer, a thin flexible ring at the periphery of said dial and luminous 110 fields on said ring.

In testimony whereof I have hereunto set my hand this 23rd day of December, 1918.

IRVING FLORMAN,
